CLIP FOR TENTERING MACHINES AND
THE LIKE

Julien Dungler, Basel, Switzerland

Application May 3, 1946, Serial No. 667,053
In France November 24, 1945

11 Claims. (Cl. 26—62)

1

My invention has for its object automatic clips for tentering machines, said clips including a base plate or table forming the lower jaw and a nipper plate or faller forming the upper jaw.

It is a recognized fact that such clips show in practice the drawback of interfering with a uniform drying of the fabric which is to be held because of the fact that the selvages dry with difficulty as they are protected against the action of the currents of hot air on one hand by the tables and on the other hand by the nipper plates forming the clips.

My invention has for its object to remove this drawback by producing an improved type of automatic clip through which the action of hot air is adapted to be exerted as directly on the selvages as on the remainder of the fabric.

It has moreover for its object an arrangement of said clips allowing the reliable introduction, without any risk of damage, of the fabric into the tentering machine in a slack state whatever may be the surplus of fabric overfed and which may be as great as desired in accordance with the amount of shrinkage which is to be imparted to the fabric through its treatment in the tentering machine.

These objects are achieved through the improvements according to my invention and which consist more particularly in that:

a. The base plate or table of the clip is executed under the form of a grid constituted by a certain number of parallel bars arranged perpendicularly to the selvage of the fabric at regular intervals and separated from one another through gaps or notches inside which the selvage of the fabric is allowed to float.

b. The movable nipper plate of the clip may be associated with a wave-forming device provided inside the clip and constituted by a series of fins or the like elements the number of which is equal to that of the notches of the table and the position and breadth of which are such as will allow their engagement into the corresponding notches of the table whereby the selvage of the fabric is constrained to form regular waves inside said notches.

c. The wave-forming device may be constituted by a series of fins or the like elements provided on the inner surface of the movable nipper plate or faller of the clip.

d. The wave-forming device may form a system independent of the clip, pivotally secured to a shaft parallel to the plane of the table or base member and provided with means cooperating with the elements carried by the movable nipper

2

plate or faller and adapted to make the movements of the faller and those of the wave-forming device depend on one another when the clip is being opened and when it is being automatically closed.

e. The movable nipper plate or faller is preferably provided with notches arranged in corresponding relationship with those of the table and shaped so as to execute in a manner known per 10 se a clamping of the selvage through a succession of points or of short lines perpendicular to or parallel with the selvage.

In order to make my invention more readily understood, I have disclosed by way of example 15 and by no means in a limitative manner different forms of execution of automatic clips provided with the improvements according to my invention, said clips being illustrated diagrammatically in accompanying drawings to which I will now 20 refer. In said drawings:

Figs. 1 and 2 are respectively side and front views of a first form of execution of an automatic clip according to my invention, illustrated in its closed position, during the drying of the fabric.

25 Figs. 3 and 4 are corresponding views of the same clip in its open position, showing the association of the clip with means for forming or rendering regular the waves or puckers of the selvage inside the notches of the clip table.

30 Fig. 5 illustrates the device for engaging the fabric with its wavy selvage inside the clip.

Figs. 6 and 7 are respectively a side and a front view of a second form of execution of the clip, Fig. 7 being drawn at a smaller scale.

35 Figs. 8 and 9 are cross-sectional views through lines VIII—VIII and IX—IX of Fig. 6 respectively of the same form of execution, also drawn at a reduced scale.

Figs. 10, 11 and 12 show respectively in side, 40 front and horizontal cross-sectional views, a third form of execution of my improved clip.

In these different figures, 1 designates the body of the clip, 2 the nipper plate or faller pivotally secured to the axis 3, said faller ending with a 45 nipping portion 4 and including an upper tail-piece 5 providing for the opening of the clip when it meets a stationary stop. 6 designates the table or base member carrying the selvage of the fabric 7 which is to be treated. This faller grips the

50 material by means of the projection 4 pressed against said fabric or other sheet material. 8, 9 designate the nozzles adapted to blow hot air on to the fabric. 10 designates the usual roller preventing the complete closing of the clip as long 55 as it rests on the fabric. When the chain moves

apart, the fabric slides under the roller 10 until it allows the passage of the latter inside a groove 11 on the table, which allows the completion of the sinking of the faller and the gripping of the fabric.

The table or base member 6 includes a series of bars 61 equally spaced one with reference to the other and separated by slots or notches 62. The width of these slots is chosen such that the selvage of the fabric may freely form waves or puckers therein without being however too large in order to avoid a deformation of the selvage under the action of the tractional stresses. The faller 2 is provided with notches 22, projections 21 being formed between said notches 22 of the faller which projections correspond to bars 61 of the grid or comb forming the table or base member 6. The shape of said projections 21 and bars 61 is such that they make point contacts. Bars 61 forming the teeth of the comb-shaped base member 6 have tapering side walls 61a (Fig. 2).

By reason of the constitution of the table or base member 6 under the form of a grid or comb and of the presence of the notches 22 in the faller 2, the drying fluid constituted in the case considered by hot air blown through the nozzles 8 and 9 acts directly and completely on the selvage, the nozzle 9 being provided if required with lateral openings allowing the oblique jets to be directed through the notches in the faller.

The regular laying of the edges of the fabric on the table or base member of the clip may be executed for instance (Figs. 3 and 4) by using a jet of compressed air or of steam blown by a nozzle 12 on to the table, said blowing being executed before the complete closing of the faller.

The regular introduction of the fabric into the clip may also be ensured through a set of two 40 endless strips of yielding material shown respectively at 13 and 14 (Fig. 5), the lower strip 13 being preferably provided with notches corresponding with those of the clip; a blower 15 expands the selvage of the fabric into wave shaped 45 formation and the faller 2 of the clip may close without risking any double clamping action.

Reverting to the form of execution illustrated in Figs. 6 to 9, it includes a fabric plaiting or wave-forming device constituted by ribs or fins 23 disposed rearwardly of the faller. The number of said fins or ribs is equal to that of the slots 62 of the table 6, said fins being adapted to engage said slots at the moment of the closing of the faller 102, which grips the selvage of the fabric 50 only when the latter will have moved from underneath the fins 23. The latter by reason of their own weight increased by that of the faller 102 make up for all the surplus of fabric and constrain said fabric to assume a more or less marked 55 sinusoidal shape. This avoids the use of blowing means although of course it is possible to associate both methods.

In the form of execution of Figs. 10 to 12 the wave forming device is constituted by a series of 65 blades or fins 17 pivotally secured to a shaft 18 parallel with the plane of the table. Two central fins include an upper projecting portion 171 defining a slide 172 inside which is engaged a rod 19 connecting two lugs 24 provided on the inner 70 surface of the faller 202. When the faller is brought into its open position, its rocking produces through the agency of the rod 19 the rising motion of the projections 171 and consequently of the wave-forming device as a whole until the 75

latter enters the position illustrated in dotted lines in Fig. 10. At the moment at which the release of the tail-piece of the faller allows the latter to fall back, the fins 17 rest on the fabric 7 which assumes a sinusoidal shape. The faller does not close completely by reason of the slope 173 holding the rod 19. When, the chains moving apart, the fabric disengages said fins, the latter sink downwardly into the notches of the table so that the faller 2 may completely close the clip and clamp the fabric.

In practice, the table 6 is preferably constituted by a ribbed or comb plate made of an inoxidisable metal and having a reduced thickness in order to assume a certain elasticity. Through this elasticity, if certain ribs forming the bars 61 of the grid plate come into contact with the fins 23 of the faller 102 before the others, they yield somewhat under the action of pressure until the latter is borne by all the ribs simultaneously.

Obviously it is possible without widening the scope of my invention to imagine various modifications and detail improvements therefor, while remaining within the scope of accompanying claims.

Having thus described the invention, what is claimed as new and desired to be secured by Letters Patent, is:

1. A tenter clip for treating fabrics, comprising a plurality of bars forming a base member and in parallel spaced apart relation perpendicular to the location of the selvage of the fabric to be treated, the upper surface of said bars being substantially convex shaped, a body member, a shaft carried by said body member and disposed parallel to the selvage of the fabric, a faller rotatably mounted on said shaft and having a plurality of teeth, said teeth being in alignment with said bars and having convex shaped end surfaces for co-action with said first mentioned convex surfaces of said bars, whereby the contact between said surfaces of the teeth and bars is substantially a linear one, and means for urging the fabric into the spaces between said bars before the clip is closed.

2. A tenter clip for engaging sheet material comprising a base member, said base member including a plurality of spaced apart bars arranged substantially parallel to each other to permit unobstructed passage of drying fluid to the selvedge of the material, a body member, a faller mounted on said body member for pivotal movement and extending to grip said material against said base member in engaging position of said faller, and means for forming waves in said sheet material within the spaces between said bars, said wave-forming means being connected for movement with said faller and being located between said faller and said base member.

3. A tenter clip for engaging sheet material comprising a base member, said base member including a plurality of spaced apart bars arranged substantially parallel to each other to permit unobstructed passage of drying fluid to the selvedge of the material, a body member, a faller mounted on said body member for pivotal movement and extending to grip said material against said base member in engaging position of said faller, and means for forming waves in said sheet material between said bars and positioned in proximity and rearwardly of said faller.

4. A tenter clip according to claim 3, wherein said wave-forming means are spaced rollers, and an axle connected to said faller and rotatably supporting said rollers, said rollers being disposed

for position between said bars, respectively, in said engaging position of said faller.

5. A tenter clip according to claim 3, wherein said base member forms a flexible comb whose teeth are constituted by said bars, whereby a give is obtained when pressure is exerted by said faller during gripping engagement thereof.

6. A tenter clip according to claim 3, wherein said bars include tapering side walls.

7. A tenter clip for engagement of sheet material comprising base-forming comb means with spaced apart open slots providing transverse passages through said comb means, a body member, faller means pivotally mounted for swinging movement on said body member, whereby in engaging position of said faller means a portion of said material is pressed by said faller means against the upper surface of said comb, whereas another portion of said material floats in said slots, and means for urging said other portion of said material into said slots and operatively connected with said faller means.

8. A tenter clip according to claim 7, wherein said latter means are positioned rearwardly of and between said faller means and said body member.

9. A tenter clip according to claim 7, wherein said comb means forms a plate supported by said body member.

10. A tenter clip for engaging sheet material, comprising a base member having a forward edge, a faller movable for position to grip said material against said base member, a body member pivotally supporting said faller to permit swinging movement of said faller toward and away from said base member, said base member being provided with spaced apart slots opening into said forward edge of said base member, spaced apart

fabric distributing means fitting said slots and connected with said faller for cooperation with the latter, said faller and said distributing means being so related to each other that the lowermost edge of the distributing means is at a level lower than that of the lowermost edge of said faller in material gripping position.

11. A tenter clip for engaging sheet material, comprising a base member having a forward edge, a faller movable for position to grip said material against said base member, a body member pivotally supporting said faller to permit swinging movement of said faller toward and away from said base member, said base member being provided with equally spaced slots opening into said forward edge of said base member, spaced apart fabric distributing means fitting said slots and connection said faller for cooperation with the latter, the number of said spaced apart distributing means corresponding to the number of said slots, said faller and said distributing means being so related to each other that the lowermost edge of the distributing means is at a level lower than that of the lowermost edge of said faller in material gripping position.
